UNITED STATES PATENT OFFICE

EARL H. BUNCE AND PHILIP M. GINDER, OF PALMEERTON, PENNSYLVANIA, ASSIGNEES
TO THE NEW JERSEY ZINC COMPANY, OF NEW YORK, N. Y., A CORPORATION OF
NEW JERSEY

ZINC FURNACE

Application filed May 29, 1930. Serial No. 458,938.

This invention relates to zinc furnaces and has for its object the provision of certain improvements in retorts for smelting zinciferous materials, and in particular for the distillation of zinciferous materials.

The invention is especially applicable in the construction of vertical built-up zinc retorts of the type described in U. S. Patent No. 1,680,726, August 14, 1928, to Breyer and Bunce, though not limited thereto. That patent describes a vertical retort structure built up of temperature resistant brick cemented together with plain butt joints. The aim of the present invention is to render such a structure more resistant to the inevitable temperature changes and resulting expansion and contraction that are incident to its use. The expansion and contraction produced by temperature changes result in stresses and strains which tend in the long run to crack the masonry of such a retort and thus shorten its life. According to the present invention, the stresses and strains produced by expansion and contraction are lessened and localized by fitting the walls of the retorts together with vertical slip joints more particularly described hereinafter. These slip joints are so constructed that each wall of the retort has room to expand and contract both horizontally and vertically without transmission of the movement to the adjoining walls with consequent production of stresses and strains. In other words, the destructive interplanar stresses which would otherwise occur at the corners of retorts of rectangular cross-section are avoided by the walls being permitted to move in their own planes.

Slip joints, according to the invention, are constructed as follows: A slot is formed in one wall into which another wall fits. At the point where the entering wall fits into the slot, the edges of the slot approach it closely enough to form an adequately tight joint. However, the slot is so constructed that the wall entering it is not in close contact with the entire inner surface of the slot. The slot is also deep enough to permit free expansion of the entering wall in a horizontal direction. Such a slot thus forms a structure resembling a stuffing box or gland. The stuffing-box or

gland thus formed may be sealed by a pulverulent refractory material which will not sinter or frit and so cause the walls to become rigidly cemented together. Suitable materials for this purpose are powdered silicon carbide, graphite, granular alumina and the like. Mixtures of flaked graphite and powdered graphite or of silicon carbide and graphite are also suitable. Such a filling material has been used in vertical zinc retorts constructed in accordance with the invention for nine months without sintering or fritting.

While the use of such a pulverulent sealing material in the stuffing-box slip joint of the invention is at present our preferred practice, it is to be understood that its use is by no means essential. The stuffing-box can be left empty, since when such a vertical retort is operated the zinc vapor that seeps into the slip joint soon becomes oxidized to zinc oxide by contact either with the air or with oxidizing gases in the combustion chamber surrounding the retort or adjacent to it. This zinc oxide together with small amounts of plastic glaze and slag that form on the surface of refractory materials when heated to the temperature at which a zinc smelting retort is operated, and when in contact with a zinc retort charge, forms a suitable seal. Such a slip joint will, shortly after the retort has been put in operation, support an internal pressure of somewhat more than $\frac{1}{2}$ inch of water without permitting any substantial leakage of zinc vapor. This degree of zinc vapor tightness is adequate for ordinary practice since vertical zinc retorts are commonly operated at an internal pressure of 0.3 inches of water.

In case the joints are filled with the pulverulent material described above, their edges are luted slightly with clay as the pulverulent material is put in so that it will not run out of the joint. Care is taken not to apply enough clay luting to bind the two walls rigidly together.

The invention will be better understood by reference to the accompanying drawings in which

Fig. 1 is a cross-section of a rectangular

vertical zinc retort with four stuffing-box slip joints constructed in accordance with the invention;

5 Fig. 2 is a perspective view of the top of the retort;

Figs. 3, 4, 5 and 6 are cross-sections of rectangular retorts embodying various modifications of the stuffing-box slip joint of the invention.

10 In the drawings, numeral 40 indicates the end walls of the vertical retorts (which may or may not be at the same time the end walls of the combustion chambers for heating the retorts), and numeral 41 indicates the side walls of the retort. The side walls are shown as built of masonry but they may likewise consist of plates of refractory metal. The side walls 41 fit into slots 42 located in the end walls. The slots 42 are only slightly 20 wider than the thickness of the side wall at the point where the side wall enters the slot; but the slot is widened a short distance beyond the point of entry of the side wall to form two open spaces 43 and 44. As will be seen by the drawings the slot is likewise so deep that there is substantial clearance between the end of the side wall and the bottom of the slot, so that an open space is left as shown at 49. These open spaces, in particular at 43 and 44, are shown as filled with pulverulent sealing material (for example one of the hereinbefore described mixtures of silicon carbide and graphite). However, these 30 spaces may, in certain circumstances, be left empty; in which case the zinc oxide formed by the oxidation of the zinc vapor seeping through and the slag formed on the retort walls will automatically form an efficient 40 sealing material soon after the retort has begun to operate.

It will be understood that the particular arrangement of brickwork shown in the drawings is merely illustrative, and that the slip 45 joints of the invention can be constructed by other methods of brick-work construction, as will be evident to those skilled in the art.

Figure 3 shows a cross section of a vertical 50 zinc retort in which the slip joints are provided with only one open space 44 to serve as a container for the pulverulent sealing material, instead of two open spaces. It will of course be understood that an open space 49 55 must be left between the end of the side wall 41 and the bottom of the slot 42 as in the construction shown in Figures 1 and 2.

Figure 4 shows two retorts set end to end with a partition wall 45 containing slots 46, 60 similar to the slots in the end wall 40, for receiving the side walls 41. In the case of these slots 46 no open spaces are provided except the wide open space between the end of the side wall and the bottom of the slot. 65 Two different forms of constructing the slots

are shown at the right and left of the partition wall, respectively.

Figure 5 shows a form of construction in which the side walls of the retort are built in two or more sections separated by columns 47 70 containing slip joints 46 similar to those shown in Figure 4.

Figure 6 shows a form of retort in which the side walls are divided into two sections fitted together by a slip joint 46, the slip 75 joint being formed by a slot in the widened end 48 of one wall into which the narrowed end of the other side wall fits. The purpose of reducing the thickness of the side wall where it enters the slot is to reduce the overall thickness of the slip joint. 80

It will be understood that the particular forms of construction shown are given merely for the sake of example. The invention is based on the surprising fact that zinc retorts 85 can be constructed so as to be zinc vapor tight by joining the walls together with slip joints so constructed that only part of the two adjoining walls are in contact at the joint, open spaces being left in the joint so that ample 90 room is left for expansion, contraction and slip of the walls. Such construction increases the durability of the vertical zinc retorts since the tendency of the retorts to crack on account of the stresses and strains set up by 95 the differential expansion and contraction of the walls is minimized.

We claim:

1. A chamber for producing zinc vapor comprising a plurality of walls of temperature-resistant material so connected one to the other that each wall may independently expand or contract, one wall of each adjacent pair of walls being provided with a stuffing box into which the other wall fits to form a 105 sufficiently tight joint to prevent the escape of zinc vapor from the chamber.

2. A zinc reduction chamber comprising a plurality of walls of temperature-resistant material so connected one to the other that each wall may independently expand or contract, one wall of each adjacent pair of walls being provided with a recessed channel into 110 which the end of the other wall fits to form a sufficiently tight joint to prevent the escape 115 of zinc vapor from the chamber.

3. A chamber for producing zinc vapor comprising a plurality of walls of temperature-resistant material so connected one to the other that each wall may independently expand or contract, one wall of each adjacent pair of walls being provided with a stuffing box into which the other wall fits to form a 120 sufficiently tight joint to prevent the escape of metal zinc from the chamber, the free space between the walls in the stuffing box being filled with heat-resistant material adapted to provide a vapor-tight joint.

4. A zinc reduction chamber comprising 125 a plurality of walls of temperature-resistant

material so connected one to the other that each wall may independently expand or contract, one wall of each adjacent pair of walls being provided with a recessed channel into which the end of the other wall fits to form a sufficiently tight joint to prevent the escape of zinc vapor from the chamber, the free space between the walls within said channel being filled with heat-resistant material adapted to provide a zinc vapor-tight joint.

5 5. A chamber for producing zinc vapor comprising a plurality of walls of temperature-resistant material so connected one to the other that each wall may independently expand or contract, one wall of each adjacent pair of walls being provided with a stuffing box into which the other wall fits to form at one place a snug joint and at another place a free space between the walls, the free space between the walls in the stuffing box being filled with pulverulent material adapted to retain zinc vapor under normal operating conditions.

10 6. A zinc reduction chamber comprising a plurality of walls of temperature-resistant material so connected one to the other that each wall may independently expand or contract, one wall of each adjacent pair of walls being provided with a recessed channel into which the end of the other wall fits to form at one place a snug joint and at another place a free space between the walls, the free space between the walls in the channel being filled with pulverulent material adapted to retain zinc vapor at the normal pressure of zinc distillation within the chamber.

15 7. A vertical zinc retort of polygonal cross-section the walls of which fit together in substantially vertical joints provided with a seal of pulverulent material adequate to retain zinc vapor at the normal pressure of zinc distillation.

20 8. A vertical zinc retort of polygonal cross-section comprising walls having joints therebetween in which the points of contact of adjoining walls enclose open spaces in the joints between the walls.

25 9. A vertical zinc retort of polygonal cross-section comprising walls having joints therebetween in which the points of contact of adjoining walls enclose open spaces in the joints between the walls, said open spaces being filled with heat-resistant material adapted to provide a zinc vapor-tight joint.

30 10. A vertical zinc retort of polygonal cross-section comprising walls having joints therebetween in which the points of contact of adjoining walls enclose open spaces in the joints between the walls, said open spaces being filled with a sealing material containing at least one of the following: silicon carbide and graphite.

35 11. A chamber for producing zinc vapor

comprising a plurality of walls of temperature-resistant material so connected one to the other that each wall may independently expand or contract, the points of contact of adjoining walls enclosing open spaces in the joints between the walls.

40 12. A chamber for producing zinc vapor comprising a plurality of walls of temperature-resistant material so connected one to the other that each wall may independently expand or contract, the points of contact of adjoining walls enclosing open spaces in the joints between the walls, said open spaces being filled with heat-resistant material adapted to provide a zinc vapor-tight joint.

45 13. A vertical zinc retort of quadrangular cross section having two refractory end walls and at least one metal side wall, the metal side wall fitting into stuffing box slip joints in the end walls in such a way that the joints are substantially impermeable to zinc vapor at normal distillation pressures.

50 14. In a vertically disposed zinc reduction retort, the combination comprising a plurality of walls each of which is built up of a multiplicity of temperature resistant brick, said walls being so connected one to the other that each wall may independently expand and contract, one wall of each adjacent pair of walls being provided with a vertically recessed channel into which a vertical end of the other wall fits.

55 15. A vertically disposed reduction retort according to the preceding claim, in which the retort is divided into a plurality of chambers separated by a dividing wall, said dividing wall connecting with opposite walls of the retort by means of a slip joint that is substantially zinc-vapor-tight.

60 16. In a zinc reduction retort, the combination comprising a vertical retort defined by a plurality of vertical walls, said vertical walls fitting together in vertical slip-joints formed by vertical channels into which adjacent walls fit snugly and which are substantially zinc-vapor tight under normal operating conditions.

65 17. In a zinc reduction retort provided with a plurality of walls, the combination comprising a slip-joint for joining the walls of the retort, said slip-joint being provided with a sealing material consisting at least in part of graphite.

70 18. In a zinc reduction retort provided with a plurality of walls, the combination comprising a slip-joint for joining the walls of the retort, said slip-joint being provided with a sealing material consisting at least in part of silicon carbide.
